CLAIM

The ornamental design for a grater box cutting board as shown and described.

DESCRIPTION

FIG. 1 is a top-facing right perspective view of the grater box cutting board showing my new design;

FIG. 2 is a top view thereof;

FIG. 3 is a bottom view;

FIG. 4 is a front elevational view;

FIG. 5 is a back elevational view;

FIG. 6 is a right-side elevational view;

FIG. 7 is a left-side elevational view;

FIG. 8 is a bottom-facing left perspective view; and,

FIG. 9 is a top-facing right perspective view showing the environment of my new design.

The broken lines are included for the purpose of illustrating the environment of the invention and form no part of the claim.
